UNITED STATES PATENT OFFICE.

WILLIAM M. SMITH, OF EVANSVILLE, INDIANA.

BOTTLE.

SPECIFICATION forming part of Letters Patent No. 651,774, dated June 12, 1900.

Application filed March 31, 1899. Serial No. 711,211. (No model.)

To all whom it may concern:

Be it known that I, WILLIAM M. SMITH, a citizen of the United States, residing at Evansville, in the county of Vanderburgh and State of Indiana, have invented certain new and useful Improvements in Bottles; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to non-refillable bottles, and has for its object the provision of a bottle which can be readily filled initially and partially or wholly emptied with ease, but which will successfully resist the introduction of fluid after having been filled in the first instance.

The invention also contemplates the provision of a bottle which will be adapted to freely receive fluid in the first instance, but which will be rendered incapable of refilling by the act of corking or stoppering the bottle after filling.

Having the foregoing and other not-specified objects in view, the invention consists of a bottle provided with a valve 30 of improved construction, held in open or suspended position in the bottle-neck in a novel manner, so as to permit the free introduction of the fluid initially, but which is disconnected and made to drop to its seat by the act of stoppering or corking the bottle and thereafter rendered adaptable to permit the discharge of the contents of the bottle as desired, while preventing introduction of any additional fluid.

The invention is set forth in detail herein-after and the novel features recited in the appended claims.

In the accompanying drawings, Figure 1 is a sectional view of my improved bottle, showing the valve in its suspended or open position as manufactured; Fig. 2, a similar view showing the stopper inserted in the neck and the valve broken off from its suspending connection and resting in its seat; Fig. 3, a cross-section taken on line $x-x$ of Fig. 1, and Fig. 50 4 a perspective detail of the valve.

The form of the bottle-body may obviously be a matter of choice, as my improvements re-

late to the construction of the neck and valve co-operating therewith. The neck 1 has an annular enlargement 2, provided with internal vertical ribs 3, which are connected by a horizontal annular guide-ring 4 at a point about midway their height. This construction defines air and fluid channels 5 between the ribs themselves and between the ring 4 and the bottle-neck. The lower ends of the ribs are notched at 6 and the upper ends of said ribs are provided with inwardly-projecting lugs 7, which overhang the guide-ring above the same.

The bottle is provided with a valve-seat 8 at the upper end of the neck portion 9, which is located below the ribs and guide-ring, and the upper portion of the neck is adapted at 10 for the reception of an ordinary cork or stopper 11.

I employ a valve 12 having a cylindrical body 13 of slightly-smaller size than the guide-ring and fitted therein. The upper end of this valve is provided with a stem 14, of reduced size, which extends above the lugs 7 in position for depression by the cork or stopper 11 when inserted in the neck, while the lower end 15 of the valve is so shaped as to correctly fit the valve-seat 8 when resting thereon and has an annular flange 16 of greater diameter than the guide-ring and projecting into the notches 6. This flange and the lugs 7 prevent the valve from dropping out of the neck when moving therein.

When the bottle is manufactured, the valve, which is of glass, is connected to one of the ribs, at the upper end thereof, by a frangible or easily-broken web or teat 17, whereby the valve is held suspended, as shown in Fig. 1. In this position the valve is off its seat and the channels 5 are entirely clear and open, and hence the fluid can be introduced into the bottle with the greatest ease. When the stopper 11 is introduced in the neck, as shown in Fig. 2, and pressed down to cork the bottle, its pressure on the stem 14 causes the glass web or teat 17 to break, whereupon the valve drops by gravity and rests in its seat. It will then be possible to discharge any amount of the fluid in the bottle by simply tilting the latter, which will cause the valve to unseat itself; but it will be impossible to introduce fluid into the bottle, as the pres-

sure of the same will hold the valve on its seat, and in this respect the flange 16 is of utility, as the pressure will act thereagainst.

Having thus described my invention, what I claim as new, and desire to secure by Letters Patent, is—

1. As a new article of manufacture, a bottle provided with a neck having a valve-seat, and a valve located in the neck above the seat and joined to the neck by a frangible connection, said valve and neck being arranged to permit the free introduction of the fluid until the frangible connection is broken.
2. In a bottle, the combination with the neck thereof, of a valve in said neck and having a frangible connection therewith, and a stopper adapted to sever or break the frangible connection of the valve when said stopper is inserted in the neck above the valve.
3. In a bottle, the combination with the neck thereof, having a valve-seat, of ribs projecting inwardly in said neck, and a valve in said neck which is held suspended above the seat by a frangible connection, said ribs providing channels for the passage of the fluid around the valve and into the bottle while the valve is suspended by its frangible connection.
4. In a bottle, the combination with the neck thereof, provided with a valve-seat, of ribs projecting inwardly in said neck and defining channels and terminating above said

seat, a guide-ring connecting said ribs above the seat and intermediate their upper and lower ends and a valve movable in said ring and adapted to rest in said seat.

5. In a bottle, the combination with the neck thereof provided with a valve-seat, of ribs projecting inwardly in said neck and defining channels, a guide-ring connecting said ribs above the seat, and a valve connected to the neck by a frangible connection and held suspended in the ring above the seat.

6. In a bottle, the combination with a neck thereof, provided with a valve-seat, of ribs projecting in said neck and defining channels, a guide-ring connecting the ribs, a valve in the ring and a lateral flange on the valve below the ring.

7. In a bottle, the combination with a neck thereof, provided with a valve-seat, of ribs projecting inwardly in said neck and defining channels, said ribs having overhanging lugs at their upper portions, a guide-ring connected to the ribs, and a valve in said ring and prevented from dropping out of the bottle by the lugs.

In testimony whereof I affix my signature in presence of two witnesses.

WILLIAM M. SMITH.
